UNITED STATES PATENT OFFICE.

EVA CONSTANCE HEYGATE, OF TANKERTON, ENGLAND.

MOVABLE BUNGALOW.

1,417,736.

Specification of Letters Patent.

Patented May 30, 1922.

Application filed July 5, 1921. Serial No. 482,404.

(GRANTED UNDER THE PROVISIONS OF THE ACT OF MARCH 3, 1921, 41 STAT. L., 1313.)

To all whom it may concern:

Be it known that I, EVA CONSTANCE HEYGATE, a subject of the King of Great Britain, residing at South Lodge, Tankerton, in the county of Kent, England, have invented new and useful Improvements in Movable Bungalows, (for which I have made application in Great Britain on Dec. 20, 1919, Patent No. 162,714,) of which the following is

10 a specification.

This invention relates to a movable bungalow which can be opened out to form a considerable number of rooms and can be closed up for travelling.

15 According to this invention the movable bungalow consists of a main floor mounted upon wheels and having partitions fixed to its upper side and a superstructure capable of sliding over the partitions. The rooms 20 are formed by six wings, two hinged on each side of the main floor and one to each end forming the floors whilst the sides and ends of the rooms are formed of flaps hinged to the wings and other flaps hinged to the partitions. The roofs of the rooms are hinged to the upper floor carried by the superstructure. The superstructure may be divided 25 into three rooms by means of partitions and is provided with a balcony supported by the 30 roofs of the lower rooms.

Referring to the accompanying drawings, Figure 1 is an elevation of the bungalow.

Figure 2 is an elevation of the bungalow showing how it is manipulated.

35 Figure 3 is an elevation of the superstructure showing three doors to the three rooms and the veranda open and in use.

Figure 4 is a side elevation of the superstructure closed and arranged for transit.

40 Figure 5 is an elevation of the superstructure showing the rear end with the supports and end partition over the staircase.

Figure 6 is an elevation of the superstructure rear end closed for transit.

45 Figure 7 is a ground plan of the bungalow opened out showing main floor and extension floors with position of the entrance hall and six rooms.

Figure 8 is a plan of the underside of the 50 ground floor showing the position of the winding gear.

Figure 9 is a side elevation of the ground floor with its wheels attached and spindle of winding gear showing at each end.

55 Figure 10 is a side elevation of the bungalow with the superstructure raised showing

position of the wires proceeding from the winding gear in the ground floor to the first floor, also showing position of the two hinged partitions dividing the three upper 60 rooms. It also shows the position when folded of the hinged roof, wings and flaps of the front and back rooms.

Figure 11 is an elevation showing end of the body with the superstructure lowered 65 for transit and the position of wires from the winding gear to the attachment to the lower edge of the superstructure.

Figure 12 is an elevation showing the end of body (with the superstructure raised) 70 exposed to show the position of the wires.

Figure 13 is a plan of the first floor, with the floor boards removed showing the disposition of the wires as they come through the floor from the gearing in the ground 75 floor and their dispersal to the pulleys on either side.

The main floor 10 is mounted on four wheels 11 and has three partitions 12, 13, 13; 12 being a central partition and 13, 13 two 80 partitions at the sides. To the main floor 10 are also fixed a partition 14 at one end and four partitions 15, 15, two at the other end and two arranged centrally. At each side of the main floor 10 are hinged wings 85 16 and to each of these wings are hinged two flaps 17. Flaps 18 are hinged to the partitions 15.

An upper floor 54 is supported by the partitions 12, 13, 14 and 15 and has hinged to 90 its sides four roofs 19. When the bungalow is unfolded four rooms are formed by the wings 16, two flaps 17, 17, and two flaps 18, 18 and a roof 19, the rooms being completed by windows 20 which when packed are 95 placed on the main floor 10 adjacent to the partition 14. At the ends of the main floor 10 are hinged two wings 21 to the sides of which are hinged wings 22. To the ends of the wings 21 are hinged flaps 23 to whose 100 ends are hinged other flaps 24. Flaps 25 to which are hinged flaps 26 are hinged to the end partitions 15. Roofs 27 to which are hinged side flaps 28 are hinged to the ends of the upper floor 54.

105 In this manner end rooms are formed of the wings 21, 22, flaps 25 and 26 forming the sides and flaps 23 and 24 forming the ends and roofs 27, 28. A staircase 29 is provided leading from one of the end rooms 110 to the upper floor 54.

The top floor consists of a superstructure

30 sufficiently large to slide over the edges of the floor 54 to which are hinged two partitions 31, 31, which divide the superstructure into three rooms. A platform 32 is 5 hinged to one side of the superstructure forming a balcony to provide access to the three rooms. The platform is supported by five triangular supports 33 hinged to its underside which supports rest upon the roofs 10 19 as shown in Figure 1. The balcony is provided with a roof 34 hinged to the underside of the main roof 35 of the superstructure, and to the roof 34 are connected pillars 36 and a safety rail 37, the ends of the pillars 36 engaging with the top of the platform 32 thereby supporting the roof. The end of the balcony is protected from the weather by three hinged shutters 38 which are secured to the balcony roof 34 and when 15 not in use fold on the front of the superstructure. At each corner of the superstructure is a hinged support 39 which rests on the roofs 28 and when not in use folds against the superstructure. Adjustable 20 screwed supports 40 are provided for supporting the side and end wings. Doors 41 are hinged to the partition 12 and other doors 42 to the partitions 15, whilst the superstructure is provided with three doors 43 25 opening on to the balcony.

The superstructure is raised and lowered by means of gearing shown in Figures 8 to 35 13. The winding gear consists of four pulleys 44 mounted on a shaft 45 carried on the underside of the main floor 10 as shown in Figure 8. At each end of the shaft 45 is a pinion 46 gearing with another pinion 47 which can be turned by means of a handle adapted to be fitted on the square end of the 40 short shaft 48. Chains 49 are secured to the bottom of the superstructure at 50, and passing over pulleys 51 to each side, pass over other pulleys 52, two supported by the partition 12 and two by one of the partitions 13, 45 and thence to the pulleys 44 on the shaft 45, in the latter cases the chains also passing round pulleys 53.

To set up the bungalow, the main floor is set in a horizontal position by means of the 50 screw supports 40 and the wheels are blocked up. The balcony platform 32 is turned down and the hinged supports 33 are set at right angles to the platform. The superstructure is now raised by turning the shaft 45 and is secured in its raised position by 55 means of thumbscrews. One of the roofs 19 is then raised and the corresponding wing 16 is lowered and brought to the same level as the main floor 10 by the supports 40. 60 The other roof 19 and wing 16 are similarly treated and the two wings 16 are bolted together. The four flaps 17 are now raised into position and the two roofs 19 are turned down and secured to them. Two of the windows 20 are fixed in position as shown in

Figure 1. The three wings 18 hinged to the partitions 15 are turned out and secured by thumbscrews to the flaps 17. The two rooms on the other side of the main floor 10 are formed in a similar manner. The roof 27 70 at one end is raised and the side roofs 28 are opened out. The wing 15 is turned down and made level with the main floor 10 by supports 40. The side wings 22 are turned over. The central flaps 23 and side flaps 24 75 are turned upwards and the roofs 27 and 28 are turned down and fixed to them. The wings 25 and 26 are turned into position and secured to the wings 24. The room at the other end is similarly manipulated. 80

It will be seen that the bungalow has six rooms on the ground floor and three rooms on the superstructure.

What I claim is:—

1. A movable bungalow consisting of a 85 main floor, wheels supporting the main floor, partitions fixed to the upper side of the main floor, a superstructure capable of sliding over the partitions, a floor in the superstructure, and partitions hinged to the floor 90 in the superstructure.

2. A movable bungalow consisting of a main floor, wheels supporting the main floor, partitions fixed to the upper side of the main floor, a superstructure capable of sliding 95 over the partitions, wings hinged to the sides and ends of the main floor, flaps hinged to the wings, other flaps hinged to the partitions, roofs hinged to the superstructure, a floor in the superstructure and partitions 100 hinged to the floor in the superstructure.

3. A movable bungalow consisting of a main floor, wheels supporting the main floor, partitions fixed to the upper side of the main floor, a superstructure capable of sliding over 105 the partitions, wings hinged to the sides and ends of the main floor, flaps hinged to the wings, other flaps hinged to the partitions, roofs hinged to the superstructure, a platform hinged to the superstructure, and supports 110 hinged to the platform and supported by the roofs.

4. A movable bungalow consisting of a main floor, wheels supporting the main floor, partitions fixed to the upper side of the main 115 floor, a superstructure capable of sliding over the partitions, wings hinged to the sides and ends of the main floor, flaps hinged to the wings, other flaps hinged to the partitions, roofs hinged to the superstructure, a 120 floor in the superstructure, partitions hinged to the floor in the superstructure, a platform hinged to the superstructure, and supports hinged to the platform and supported by the roofs.

5. A movable bungalow consisting of a main floor, wheels supporting the main floor, partitions fixed to the upper side of the main floor, a superstructure capable of sliding over 125 the partitions, a shaft mounted on the under- 130

side of the main floor, pulleys on the shaft and on the partitions, and chains passing round the pulleys and adapted to raise the superstructure.

- 5 6. A movable bungalow consisting of a main floor, wheels supporting the main floor, partitions fixed to the upper side of the main floor, a superstructure capable of sliding over the partitions, wings hinged to the sides and 10 ends of the main floor, flaps hinged to the wings, other flaps hinged to the partitions, roofs hinged to the superstructure, a floor in the superstructure, partitions hinged to the 15 floor in the superstructure, a platform hinged to the superstructure, supports hinged to the platform and supported by the roofs, a shaft mounted on the underside of the main floor, pulleys on the shaft and on the partitions, and 20 chains passing round the pulleys and adapted to raise the superstructure.

- 15 7. A movable bungalow consisting of a main floor, wheels supporting the main floor,

partitions fixed to the upper side of the main floor, a superstructure capable of sliding 20 over the partitions, wings hinged to the sides and ends of the main floor, flaps hinged to the wings, other flaps hinged to the partitions, roofs hinged to the superstructure, a floor in the superstructure, partitions hinged to the 25 floor in the superstructure, a platform hinged to the superstructure, supports hinged to the platform and supported by the roofs, a shaft mounted on the underside of the main floor, pulleys on the shaft and on the partitions, 30 and chains passing round the pulleys and adapted to raise the superstructure.

In testimony that I claim the foregoing as my invention I have signed my name this 9th day of June 1921.

EVA CONSTANCE HEYGATE.
